UNITED STATES PATENT OFFICE.

MORTON C. TALCOTT, OF HARTFORD, CONNECTICUT, ASSIGNOR TO THE BILLINGS & SPENCER COMPANY, OF HARTFORD, CONNECTICUT, A CORPORATION OF CONNECTICUT.

DROP HAMMER.

Application filed April 1, 1925. Serial No. 19,842.

The invention is an improvement in die bunters for the lower dies of drop hammers. Heretofore such dies have been secured to a shoe which is secured in an undercut groove in the hammer base and tightened therein by means of a wedge driven between the edge of the shoe and the side of the groove in the base. The attachment of the die to the shoe has been made by means of an undercut tenon groove also made tight by a wedge and secured against movement on the shoe, in the direction of the tenon and groove, by means of the usual die bunters which are fixed in the shoe. In such mounting the vibration of the hammer shocks has a tendency to displace the shoe in its groove thereby shifting the die out of registry with the upper die carried by the reciprocating hammer. The effort to prevent such displacement as by further tightening the shoe wedge, has resulted in the fracture, by splitting, of many hammer bases, and consequent loss of time and expense, and such mounting has the further objection that work must be interrupted from time to time in order to tighten the wedge.

According to the present invention these objections are overcome by doing away with the usual bunters to secure the die relatively to the shoe and substituting for them a pair of cross bars forming a direct connection between the die and the base or frame of the hammer independently of the shoe, as below explained.

In the accompanying drawings Figure 1 represents a drop hammer having the invention applied;

Figure 2 a horizontal enlarged plan of the hammer base;

Figure 3 a central vertical section thereof; and,

Figure 4 a detail section of the bunter bar seat.

The drop hammer shown will be understood to represent nothing more than a conventional type of board drop hammer, 1 being the base casting, 2 the uprights which carry the hammer guides 3, and 4 being the head structure in which the lifting rolls and board clamp are mounted. In the present case the head structure has two pairs of lifting rolls, but this fact has no bearing on the present invention. The frame

uprights 2 are keyed and adjustably bolted to the base in the usual, or in any suitable manner not necessary to be described, and the base 1 is provided, between the uprights, with the usual undercut groove or other seat, to receive the shoe 5 which latter is tightened therein by the wedge 6 or by any other equivalent means. The die 7 is secured to the shoe by means of a dovetailed tenon 8 wedged in an undercut groove in the top of the shoe, by the wedge 9 as customary.

Sidewise or lateral registry of the lower die 7 with the upper die 10, carried on the hammer 11, is established by lateral bodily adjustment of the uprights 2 with respect to the base; the means for such adjustment are only partially indicated in the drawings, but are well understood. Registry of the die in a depthwise or front and rear direction is produced in the first instance and thereafter maintained by the two clamp screws 12, each of which is carried in the central region of a bunter bar 13. These bars span the central opening of the hammer frame at front and rear, and are firmly clamped or otherwise secured to the frame at their ends. Preferably the bars are seated in sockets 14 formed in the upper corners of the base casting itself underneath the bottom surfaces of the uprights 2, which surfaces form the upper walls of the sockets, as shown more clearly in Fig. 4, and they are clamped in these sockets by the two tie bolts 15, which tie them rigidly together and against the front and rear of the frame. The tie bolts thus act as tension members to take the strain of the bunter screws 12 and the sockets keep the cross bars from working out of position, vertically, under the effect of vibration; they also assist in assembling the bars and tie bolts in the frame as will be evident.

It will be apparent that the bunter bars as thus organized hold the die in fixed relation to the frame or base of the hammer, independently of the shoe, and in consequence, that any displacement which may occur of the latter will not affect the die. Accordingly it is not necessary to tighten the wedge 6 to an extent that might endanger the base casting, nor is it necessary to drive either the wedge 6 or the die-wedge 9 as tightly, nor as often, as formerly, while the cross bunter

bars afford ample strength for clamping the die firmly in permanent registry and are not themselves likely to break or become displaced.

6. I claim:

1. In a drop hammer, the combination of the hammer base, a shoe removably seated thereon, a die removably seated on the shoe and bunters for the die comprising cross bars spanning the central opening of the hammer frame and engaged at their ends with said frame and provided at their intermediate portions, with means to hold the die.
10. 2. In a drop hammer, the combination of the hammer base, a shoe removably seated thereon, a die removably seated on the shoe and a bunter for the die comprising a cross bar engaged by its ends with seats on the hammer frame adapted to prevent vertical displacement of said bar and provided with means to hold the die.
15. 3. In a drop hammer, the combination of the hammer uprights and base, a shoe secured on the base, a die secured on the shoe and a bunter for the die comprising a cross bar engaged with sockets in the hammer frame, said sockets being formed in part by corner recesses in the base casting and in part by the under surfaces of said uprights.
20. 4. In a drop hammer, the combination of the hammer frame including its base, a shoe secured to the base, a die secured to the shoe, a cross bar bunter for the die spanning the central opening of the hammer frame, tension members clamping the ends of said bunter to the frame and a clamp screw in the bunter bar adapted to hold the die.
25. 5. In a drop hammer, a frame having a base portion, uprights arising therefrom, a hammer guided in said uprights for reciprocating vertical motion, a shoe on said base between said uprights, a die adjustably secured to said shoe, and a clamping device for adjusting said die and holding it in position and including a bar extending across the front of the frame and supported at its ends

thereagainst, a bar extending across the back of the frame and supported at its ends thereagainst, tie rods connecting said bars and adjustable screws carried by said bars and engaging said die.

6. In a drop hammer, a base portion, a pair of uprights rising therefrom, a hammer guided in said uprights for reciprocating vertical motion, a shoe removably positioned in said base between said uprights, a die removably attached to said shoe, and a removable bar secured to said base independently of said shoe and provided with means for holding said die in adjusted position relative to the die carried by said hammer.

7. In a drop hammer, a frame comprising a base and a pair of uprights rising therefrom, a vertically reciprocating hammer guided in said uprights, a shoe removably seated in said base, a die adjustably seated on said shoe and two means for holding said die, one of said means being a direct connection between said die and shoe and serving to prevent lateral die movement, and the other being a direct, transversely extending connection between said die and said frame independent of said shoe, and serving to prevent depthwise die movement.

8. In a drop hammer, a frame comprising a base and two uprights laterally adjustable thereon, a vertically reciprocating hammer guided in said uprights, a die-holding shoe having a dovetailed adjustable connection with said base and a die having a dovetailed adjustable connection with said shoe, in combination with means forming a direct connection between said die and said frame, independently of said shoe, for retaining the die against displacement in the direction of said dovetailed connections, said means including a bar extending transversely of the machine and being movable with respect to the machine to permit removal of the die from its dovetail groove.

In testimony whereof, I have signed this specification.

MORTON C. TALCOTT.
